DESIGN FOR A POTTERY ANIMAL FIGURE

Irving Miller, New York, N. Y., assignor to Spaulding China Company, Inc., New York,
N. Y.

Application May 23, 1944, Serial No. 113,725

Term of patent 3½ years

(Cl. D29—23)

To all whom it may concern:

Be it known that I, Irving Miller, a citizen of the United States, residing at 179-39 Tudor Road, Jamaica Estates, in the county of Queens and State of New York, have invented a new, original, and ornamental Design for Pottery Animal Figure, of which the following is a specification, reference being had to the accompanying drawing, forming part thereof. The figure is a perspective view of a pottery animal figure, showing my new design. The opposite side of the figure is the same as that shown in the drawing.

I claim:

The ornamental design for a pottery animal figure, substantially as shown and described.

IRVING MILLER.
